UNITED STATES PATENT OFFICE.

OBADIAH HOLMES, OF BLUE SPRINGS, MISSOURI.

LATCH AND LOCK COMBINED.

SPECIFICATION forming part of Letters Patent No. 606,550, dated June 28, 1898.

Application filed July 27, 1897. Serial No. 646,069. (No model.)

To all whom it may concern:

Be it known that I, OBADIAH HOLMES, a citizen of the United States, and a resident of Blue Springs, in the county of Jackson and State of Missouri, have invented certain new and useful Improvements in a Combined Door Lock and Latch; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 is a plan view of a lock embodying my invention, with the cap-plate removed and the bolt in unlocked position. Fig. 2 is a similar view with the cap-plate partly broken away and the bolt in locked position. Figs. 3, 4, and 5 are detail sectional views showing the movable block and tumblers in different positions. Fig. 6 is a front view of the movable block and tumblers. Fig. 7 is a side view of one of the tumblers removed, and Fig. 8 is a side view of a key adapted to the lock.

This invention is designed to provide a combined lock and latch which obviates the employment of separate lock and latch bolts, which is of simple, cheap, and durable construction, and which can be used either as a mortise or as an outside lock and latch.

With these objects in view the invention consists in the novel construction and combination of parts, all as hereinafter described, and pointed out in the appended claims.

Referring to the accompanying drawings, the letter A designates the case, which is of the usual flat rectangular form, except that it may be considerably narrower than those cases which are made to contain separate lock and latch bolts.

A' is the removable cap-plate of the case.

B indicates the keyhole, and C the hub, which is fitted to receive the usual knob-spindle and carries within the case the actuating-cam lugs or projections C'.

D designates the combined lock and latch, which is formed within the case with the two legs d, which slide in contact, respectively, with the inner faces of the upper and lower walls of the case. It also has a central slotted portion D', which seats a protracting-spring E, whose fixed abutment is at F.

G designates a movable block or bolt which is operated by the key of the lock to secure the latch against retraction and thereby form the lock, and by the reverse movement of the key to release the latch. Said block or bolt is seated at the inner end portion of the case between a ward-plate H, which forms a bearing for one side thereof, and a fixed lug or abutment I, which forms the bearing for its opposite side. Its length is sufficiently less than the width of the case to form a space g between one end thereof and the wall of the case when it is in proper position, such space being adapted to receive therein one leg d of the latch when the latter is retracted. At its opposite end it is cut away to form a similar space g', which is designed to receive the other leg of the latch. Its rear face is formed with a V-shaped notch k to receive the key and is also grooved to form parallel wards k', which are cut by the said notch. K designates tumblers which are seated in the grooves between these wards. Each of the tumblers is pivoted at k² at one end and has at its opposite end a tooth or projection k³. Seated within the block is a coiled spring L, which presses against the free or toothed ends of the tumblers to press them outwardly of their seats. Each tumbler also has at its central portion a depression l with inclined lateral walls l' and a straight bottom wall l². These depressions are located at points corresponding to the notch k.

The ward-plate H has a semicircular recess h opposite to the notch k and is grooved to form the semicircular wards h', which are respectively in the planes of the corresponding opposite wards k'. In that portion of the face of the plate which is opposite the toothed ends of the tumblers K are formed small notches or depressions m m, in engagement with which the teeth of said tumblers are held by the spring L when the block or bolt G is in its normal or non-locking position. m' m' are two similar notches or recesses with which said teeth engage in a similar manner when the said block or bolt is in its locking position.

P designates a key which is adapted to the particular lock shown.

The operation is as follows: In the normal position of the block or bolt G the latch can be freely retracted by the operation of the

knob-spindle, the inner ends of the legs *d* sliding freely into the spaces *g* and *g'*. The key being turned in the proper direction and engaging the wards *k'*, the bits of the key ride down the inclined walls *l'* at one side of the depressions *l* of the tumblers and into engagement with the straight walls *l*² thereof, thereby forcing the tumblers back into their seats against the pressure of the spring *L*, their teeth *k*³ being withdrawn from engagement with the notches *m m'*. As soon as these teeth are so withdrawn the pressure of the key upon the tumblers is sufficient to move the block or bolt endwise sufficiently to close the space *g* against the entrance of the leg *d* of the latch and thereby prevent the retraction of the same. As the key is further turned the bits ride up the opposite inclined walls *l'*, thereby releasing the tumblers from the pressure thereof, and the teeth are at once thrown into engagement with the recesses *m'*. Further idle movement of the key is upon the wards *h'*.

In unlocking the operation is the reverse of that just described, the tumblers being first forced back out of engagement with the recesses *m'*, the block or bolt being moved back to its normal position, and the tumblers then being released and being thrown by the spring into engagement with the recesses *m*.

Any suitable number of tumblers may be employed with a corresponding adaptation of the parts *G* and *H* and of the key.

It will be observed that the arrangement of the tumblers and of the ward-plate is such that the tumblers cannot be operated except by a key especially adapted thereto.

The sliding block or bolt being placed behind the latch and without lateral projection to either side thereof does not require an increased width of lock-case for its accommodation. It will be noted that by reason of this fact it is possible to use a very narrow lock-case.

Having thus described my invention, what I claim as new, and desire to secure by Letters Patent, is—

1. The combination with a reciprocating latch, its protracting-spring, and means for retracting said latch, of the endwise-movable block or bolt adapted to be moved into the path of the latch behind the inner end of the same to secure it against reciprocation, spring-pressed tumblers carried by seated in and

pivoted within parallel recesses or grooves in said block or bolt and having means whereby they are adapted to engage with a stationary part of the lock in both positions of said block or bolt, and a suitable key adapted to said grooves or recesses and to engage with said tumblers to retract them from engagement with said stationary part, and also to effect an endwise movement of the said block or bolt, substantially as specified.

2. The combination with the case, the reciprocating latch, its protracting-spring and retracting device, of an endwise-movable block or bolt adapted to be moved into position to lock said bolt against retraction, said block or bolt having parallel wards and a V-shaped notch or recess cutting through the said wards, the pivoted spring-pressed tumblers seated between the said wards and having each a tooth or projection at its free end portion, said tumblers also having depressions therein formed with inclined lateral walls and straight bottom walls, a stationary ward-plate having recesses therein to receive the teeth or projections of the said tumblers in both positions of the sliding block or bolt, and a suitable key adapted to said wards and tumblers, substantially as specified.

3. The combination with the reciprocating latch, of the slideable block or bolt arranged to be moved behind said latch to lock it against retraction, said block or bolt having parallel wards in one face or edge and a V-shaped notch or recess cutting through the said wards, pivoted spring-pressed tumblers seated between the said wards and having each a tooth or projection at its free end portion, a stationary ward-plate having recesses adapted to receive the teeth or projections of the said tumblers and also a semicircular recess whose wall is formed with a series of wards which are respectively in the planes of the corresponding wards of the said block or bolt, and a suitable key adapted to said wards and tumblers, the latter having intermediate bent or depressed portions upon which the key is adapted to act, substantially as specified.

In testimony whereof I affix my signature in presence of two witnesses.

OBADIAH HOLMES.
